UNITED STATES PATENT OFFICE.

ISAAC O. MEDDOWS, OF BONHAM, TEXAS.

IMPROVEMENT IN RUNNING-GEAR FOR VEHICLES.

Specification forming part of Letters Patent No. 136,331, dated February 25, 1873.

To all whom it may concern:

Be it known that I, ISAAC O. MEDDOWS, of Bonham, in the county of Fannin and State of Texas, have invented certain new and useful Improvements in Gearing for Road-Wagons, Carriages, &c., of which the following is a specification:

This invention relates to the mode of constructing the gearing of road-wagons, carriages, &c.; and it consists in forming the head-block in two pieces, with a central eye or opening for the passage of the axle; a groove for the reception of the king-bolt of the rocking bolster; and wrought-iron brackets or loops for the attachment of the coupling-pole, tongue, &c.; also, in friction-boxes for the axles, formed in two parts, the upper having a key or bearing for the journals of a friction-roller placed within the box over the axle, and the lower part of the box having a key or bearing placed immediately beneath the axle; the whole forming friction-boxes, which are firmly bolted to the bolsters by means of wrought-iron bands which encircle the boxes; and in further details of construction hereinafter more fully set forth.

In the drawing, Figure 1 is a top or plan view of the gearing embodying my invention. Fig. 2 is a side view of the same. Fig. 3 represents an end view. Figs. 4, 5, 6, 7, 8, and 9 are detached views of my improvements in wagons.

Like letters of reference indicate corresponding parts.

The letters A A' represent the two parts forming the head-block. They are of cast-iron and of similar construction, so that when brought together a central eye or opening is formed for the passage of the axle-tree, and a groove in the upper part of the block is left for the reception of the king-bolt a. B B' represent wrought-iron brackets or loops bolted to the front and rear of the head-block for attaching the tongue and coupling. The sections of the head-block are extended downward, forming two arms or projections, b b', which embrace the said bolster, and form the means for securing the head-block upon the sand-bolster C, by bolts and nuts or otherwise. D D' represent the two sections forming the friction-box for the axles, the sections being confined together by a wrought-iron band, E, passing

around the entire box and fastened with bolts to the bolster C. d d' represent what I term "friction-keys" or bearing-surfaces, composed of cast-steel. The one, d, in the upper section, D, of the box, is made of such a size as will accommodate the journal f of a friction-roller, F; the lower one, d', must be of such size as will admit of free movement of the axle-tree H. The upper section of the box D is by far the larger and stronger portion, and is recessed, as shown in Figs. 6 and 8, for the reception of the friction-roller F. The lower section D' is little more than a shell for containing the key or friction-surface d', this construction being necessary, as the upper portion has to bear the weight of the load and the jar of travel. e are loops or brackets bolted to the band E as fastenings for the guide-braces of the tongue.

The construction of the several friction-boxes and their relation to the axle-trees are similar, and such as above described. Their mode of attachment to the bolster-coupling tongue I will now proceed to describe.

The head-block and the two friction-boxes of the forward axle-tree are placed over the sand-bolster C, and secured thereto by means of the bolts and nuts or other suitable devices passing through the downwardly-projecting portions b b' of the head-block and bands E E which surround the friction-boxes. The tongue is connected to the head-block by a wrought-iron strap passing around the end of the tongue and through the loop B on the head-block. Across the tongue, at right angles to the same, is arranged a cross-bar, I, which connects with the guide-braces g g, said guide-braces being secured at one end to the loops e of the band E, and at the other end to the tongue in any suitable manner. K, Figs. 1 and 2, represents the rocking bolster, which is provided with circle-bars k, (shown in dotted lines,) placed underneath the bolster, immediately over the friction-boxes, and secured to the bolster by braces fastened near the ends thereof. L represents the coupling or reach secured to the head-block by a wrought-iron strap passing through the loop or bracket B', and having a stay or brace, l, extending from the coupling to the sand-bolster C. M represents the rear bolster, which is placed over the friction-boxes and axle-tree, and connected to the boxes by being

bolted to the bands E which bind the sections of the boxes together. N are the hounds, secured at one end to the boxes E by the brackets before described, and at the other end to the coupling L. A rod, O, extends across from one to the other of the rear axle-boxes, so as to brace them and afford greater resistance to any lateral strain.

Having described my invention, I claim—

1. The head-block, provided with a central eye or opening for the passage of the axle-tree, a groove for the reception of the king-bolt, with a loop or bracket in front and rear, as and for the purpose specified.

2. The friction-boxes, constructed in two parts and provided with a friction-wheel, F, metal-bearing-surfaces or keys $d d'$, and secured by a metallic band or other suitable clamping devices, substantially as specified.

3. The head-block having brackets B B', and the friction-boxes having loops e e, in combination with the tongue G and guide-braces g, substantially as and for the purpose set forth.

4. The head-block with its bracket or loop B', in combination with the coupling L, stay or brace l, and sand-bolster C, substantially as specified.

In testimony that I claim the foregoing I have hereunto set my hand this 30th day of September, 1872.

ISAAC ORSON MEDDOWS.
